SIGNAL DEVICES

Leif Arneson, Minneapolis, Minn., assignor to Minneapolis-Honeywell Regulator Company, Minneapolis, Minn., a corporation of Delaware

Application November 5, 1958, Serial No. 772,118

6 Claims. (Cl. 338—91)

This invention relates to the field of electrical instruments, and more specifically to non-linear voltage dividers. It is known to construct voltage dividers so that the resistance gradient for a given slider displacement is not everywhere the same, and it is also known to construct voltage dividers with uniform resistance gradients and with mechanical movement between the slider and its drive shaft which introduces non-linearity into the motion transmitted. Devices of the latter type have heretofore required gear means, however, and this introduces inaccuracies due to imperfect gear cutting, to back lash, and in general to the difficulties inherent in geared mechanism.

The principal object of this invention is to provide a voltage divider, having a linear resistance element and a non-linear output, in which no gears are required. Another object of the invention is to provide a voltage divider in which a four bar linkage and a cam and follower are inserted between the drive shaft and the slider, to give a desired non-linearity of operation. A specific object of the invention is to provide a novel mechanical linkage.

Various other objects, advantages, and features of novelty not particularly enumerated above which characterize my invention are pointed out with particularity in the claims annexed hereto and forming a part hereof. However, for a better understanding of the invention, its advantages, and objects attained by its use, reference should be had to the subjoined drawing, which forms a further part hereof, and to the accompanying descriptive matter, in which I have illustrated and described a preferred embodiment of my invention.

In the drawings Figure 1 is a schematic showing of a voltage divider according to the invention, and Figures 2 and 3 are longitudinal and transverse sectional views of one physical embodiment of the invention.

Figure 1 shows an input shaft 10 pivoted for rotation about an axis 11, and an output shaft 12 pivoted about the same axis. Shaft 10 carries a link 13 and shaft 12 carries a link 14. Pivoted to links 13 and 14 about axes 15 and 16 respectively are a pair of further links 17 and 20 having a common pivotal axis 21. A circular cam follower 22 is pivoted about axis 21, and moves in contact with a cam 23. A spring 24 acts on links 13 and 14 to decrease the angle between them, and thus urge follower 22 into contact with cam 23. A circular resistance element 25 is mounted concentric with axis 11, and a slider 26 is carried by link 14 for continuous engagement with element 25.

It will be evident that as long as cam 23 defines a circle about axis 11, rotation of input shaft 11 results in rotation of output shaft 12 through the same angle. However if cam 23 is not a circle, movement of input shaft 10 results in a greater rotation of output shaft 12 if the radius of the cam about axis 11 is decreasing and less rotation of the output shaft if the radius is increasing. By suitably designing the cam, the desired nonlinearity

2

may be inserted between shaft 11 and slider 26, even to the extent of reverse operation.

Figures 2 and 3 show a preferred embodiment of the invention, elements identified in Figure 1 being given the same numbers in Figures 2 and 3.

Input shaft 10 is shown to pass through a central bearing hole in a cover 30, and to be pivoted in a boss 31 extending upward from the base 32 of a casing 33. Link 14 is freely pivoted on the lower reduced end of shaft 10, which thus functions as shaft 12 of Figure 1, and an aperture 34 is provided in link 14 to receive the end of spring 24. Slider 26 is shown as welded to link 14 and as engaging the annular resistance element 25 which is received in a recess in casing 33. Link 13 is shown as fixed to shaft 10 and the other end of spring 24 is received by a hole in the link. Cam 23 is shown as carried on a shoulder in housing 33, for engagement by cam follower 22; one outline for cam 23 is best shown in Figure 2.

Numerous objects and advantages of my invention have been set forth in the foregoing description, together with details of the structure and function of the invention, and the novel features thereof are pointed out in the appended claims. The disclosure, however, is illustrative only, and I may make changes in detail, especially in matters of shape, size and arrangement of parts, within the principle of the invention, to the full extent indicated by the broad general meaning of the terms in which the appended claims are expressed.

I claim as my invention:

1. Apparatus of the class described comprising, in combination: a four bar linkage including an input link and an output link, having a first common pivotal axis and a pair of intermediate pivotal axes, and a pair of independent links, having a second common pivotal axis and a pair of independent pivotal axes common with the independent pivotal axes of said input and output links; means for causing rotation of said input link; spring means continuously acting to maximize the distance between said common axes; cam and follower means for limiting said distance, so that rotation of said output link is linear with rotation of said input link when said distance remains constant, and becomes nonlinear when said distance varies; a voltage divider including a resistance member and a contact member; and means connecting said output link to said voltage divider for causing relative movement between said members.

2. Apparatus of the class described comprising, in combination: a four bar linkage including an input link and an output link, having a first common pivotal axis and a pair of independent pivotal axes, and a pair of intermediate links, having a second common pivotal axis and a pair of intermediate pivotal axes common with the independent pivotal axes of said input and output links; spring means continuously acting to minimize the angle between said input and output links and hence to maximize the distance between said common axes; means for causing rotation of said input link; means for limiting said distance including a cam extending around said first common axis and a cam follower carried by said second common axis; a voltage divider including a circular resistance member and a contact member rotatable with respect thereto; and means connecting said output link to said contact member, so that rotation of said contact member is linear with rotation of said input link when said distance remains constant, and becomes nonlinear when said distance varies.

3. Apparatus of the class described comprising, in combination: a four bar linkage including an input link and an output link, having a first common pivotal axis and a pair of independent pivotal axes, and a pair of intermediate links, having a second common pivotal axis and a pair of intermediate pivotal axes common with the inde-

pendent pivotal axes of said input and output links; means for causing rotation of said input link; spring means continuously acting to minimize the angle between said input and output links and hence to maximize the distance between said common axes; means for limiting said distance including a cam extending around said first common axis and a cam follower carried by said second common axis; a voltage divider including a circular resistance member and a contact member rotatable with respect thereto; means mounting said resistance member so that its center is substantially on said first common axis; and means connecting said output link to said contact member, so that rotation of said contact member is linear with rotation of said input link when said distance remains constant and becomes nonlinear when said distance varies.

4. Apparatus of the class described comprising, in combination: a four bar linkage including an input link and an output link, having a first common pivotal axis, and a pair of independent pivotal axes, and a pair of intermediate links, having a second common pivotal axis and a pair of independent pivotal axes common with the independent pivotal axes of said input and output links; means for causing rotation of said input links; spring means continuously acting between said input and output links to minimize the angle therebetween and hence to maximize the distance between said common axes; means for limiting said distance including a cam extending around said first common axis and a cam follower carried by said second common axis; a voltage divider including a circular resistance member and a contact member rotatable with respect thereto; and means connecting said output link to said contact member, so that rotation of said contact member is linear with the rotation of said input link when said distance remains constant and becomes nonlinear when said distance varies.

5. Apparatus of the class described comprising, in combination: a four bar linkage including an input link and an output link, having a first common pivotal axis, and a pair of independent pivotal axes, and a pair of intermediate links, having a second common pivotal axis and

5 a pair of intermediate pivotal axes common with the independent pivotal axes of said input and output links; means for causing rotation of said input links; spring means continuously acting to minimize the angle between said input and output links and hence to maximize the distance between said common axes; means for limiting said distance including a cam extending around said first common axis and a cam follower pivoted about said second common axis; a voltage divider including a circular resistance member and a contact member rotatable with respect thereto; and means connecting said output link to said contact member, so that rotation of said contact member is linear with rotation of said input link when said distance remains constant and becomes nonlinear when said distance varies.

10 6. Apparatus of the class described comprising, in combination: a four bar linkage including an input link and an output link, having a first common pivotal axis and a pair of independent axes, and a pair of intermediate links, having a second common pivotal axis and a pair of independent pivotal axes common with the independent pivotal axes of said input and output links; means for causing rotation of said input links; spring means continuously acting to minimize the angle between said input and output links and hence to maximize the distance between said common axes; means for limiting said distance including a cam extending around said first common axis and a cam follower pivoted about said second common axis between said intermediate links; a voltage divider including a circular resistance member and a contact member rotatable with respect thereto; and means connecting said output link to said contact member, so that rotation of said contact member is linear with rotation of said input link when said distance remains constant and becomes nonlinear when said distance varies.
